OF CHICAGO, ILLINOIS.

ADDING-MACHINE.

1,070,146.

Specification of Letters Patent. Patented Aug. 12, 1913.

Application filed December 15, 1910. Serial No. 597,435.

To all whom it may concern:

Be it known that I, ROBERT H. LITTLE, a citizen of the United States, residing at Chicago, in the county of Cook and State of Illinois, have invented certain new and useful Improvements in Adding-Machines, of which the following is a specification.

My invention relates in general to adding machines and more particularly to small 10 sized machines which are adapted to be readily and easily moved about on a desk or table and carried from desk to desk as occasion requires.

One object of my invention is the provision 15 of an adding machine of the character indicated which shall have but a single value member or operating member, said member being so constructed and mounted that it is capable of variable actuating movements de- 20 pending upon the number to be set up.

Another object is to so connect the vari- 25 ably movable value member with the number wheel that operative movement of the value member will cause a proportionate shifting movement of the number wheel.

Still another object is the provision of 30 mechanism for preventing overthrow of the number wheel beyond the proportionate shifting movement imparted to it by the value member.

A further object is to provide means for 35 retaining the number wheel in shifted position during the return of the value member to normal position, and releasing means for disconnecting said retaining means to permit the resetting of the number wheel.

An additional object is to produce a ma- 40 chine which shall be small, light, simple in construction, cheap to manufacture and easy to operate, and at the same time strong, durable, accurate and efficient in its opera- 45 tion.

Other objects and advantages of my in- 50 vention will be apparent as it becomes bet- 45 ter understood by reference to the follow- 55 ing description when taken in connection with the accompanying drawings illustrating one preferred embodiment thereof.

Referring to the drawings—Figure 1 is 50 a plan view of an adding machine embodying my invention. Fig. 2 is an elevation thereof partially in section. Fig. 3 is a view similar to Fig. 1 with the top plate re- 55 moved to more clearly show the operating

mechanism. Fig. 4 is a fragmentary view 55 of the number wheel retaining and releasing devices. Fig. 5 is a detail view of cer- 60 tain parts shown in Fig. 4 looking at the bottom thereof; and Fig. 6 is a sectional view on the line 6—6 of Fig. 1 showing in 65 dotted lines the overthrow stop in operative and in full lines in inoperative position.

On the drawings 10 designates the bed or base of the machine which is preferably circular in shape and has centrally mounted 65 thereon a vertically disposed rotatable shaft 11 carrying a circular number wheel 12. The number wheel is provided around its periphery with serrations or radially disposed teeth 13 and its upper face has arranged 70 thereon in proximity to the spaces between the adjacent teeth, numbers ranging consecutively from zero to 99 inclusive. A stationary plate 14 positioned above the number wheel has a notch 15 on its edge dis- 75 posed over the numbers on the wheel, the various parts of the machine being so ar- ranged that the number zero is visible in this notch when the parts are in normal position and the total of the various numbers added 80 is displayed and read at this position.

A semi-circular plate 16 may be employed 85 to cover the operating mechanism of the machine and provide a bearing for the upper end of the shaft 11, although it will be evi- 90 dent that the shaft may be otherwise mount- 95 ed and the various parts may be covered and protected in any other preferred manner or left exposed if desired.

An operating member or value member 17 90 comprises a lever fulcrumed to swing in an arc about the shaft 11 and a plate projecting laterally from the arm and having its outer edge provided with a series of notches 18. The plate is provided with a series of num- 95 bers ranging from 1 to 9 inclusive, arranged consecutively adjacent the notches, nine in number, formed on the outer edge of the plate, and this notched edge is disposed at an angle to the adjacent radial edge of the 100 stationary cover plate 16 so that when the value member is in normal position the notch numbered 1 is nearest the edge of the plate, and the notch numbered 9 is farthest from said edge, as shown in Fig. 1. The value 105 member is normally held in the position shown in Figs. 1 and 3 by a tension spring 19 attached at one end to a stud 20 fixed on

the base 10 and at its other end to the arm 21 projecting from the value member beyond its fulcrum 11. A pin 22 surrounded with a cover 23 of rubber or other yielding material is disposed between the plates 14 and 16 to form a buffer against which the outer end of the operating member abuts when it is returned to normal position by the tension spring 19. The yielding cover is provided for the purpose of reducing the noise and shocks incident to the operation of the machine.

Near the outer end of the lever portion of the operating or value member 17, there is pivoted at 24 a pawl 25 which is yieldingly urged into engagement with the teeth 13 on the number wheel by a spring 26 secured to the underside of the value member 17 and having its free end positioned to press against a pin 27 projecting laterally from the upper side of the pawl 25. It will be evident that when the value member is moved about the vertical shaft 11 in a counter-clockwise direction looking at Figs. 1 and 3, the pawl 25 will engage with one of the teeth on the periphery of the number wheel and rotate the number wheel about its axis a distance equal to the movement of the value or operating member. When the operating member is released it will be returned to normal position against the stop or buffer 22 by the tension spring 19, the pawl 25 on this return movement sliding over the outer ends of the teeth 13. In order to prevent backward rotation of the number wheel upon the return movement of the operating member, a holding pawl 28 is provided which is pivotally mounted at 29 on the elevated bottom 30 of the base of the machine. This pawl as shown in Figs. 4 and 5 is disposed beneath and adjacent to the periphery of the number wheel and is provided with a laterally projecting tooth or shoulder 31 which is inclined relatively to the teeth on the number wheel to permit the number wheel to be shifted in a counter-clockwise direction but to engage with the rear face of the teeth 13 and prevent backward movement of the number wheel when the pawl 25 is disengaged therefrom upon the return movement of the operating member. The pawl 28 is yieldingly urged into engagement with the number wheel by a spring 32 fastened to the elevated base 30 and having its free end disposed to press against the outer face of the pawl, and yieldingly maintain the same in operative position. The inward movement of the pawl 28 is limited by the abutment 32'.

In order to permit the number wheel to be returned to normal position I have provided a device for simultaneously disengaging pawls 25 and 28 from engagement with the teeth 13. This device comprises a member 33 pivotally mounted at 34 and hav-

ing its free end provided with a hook or finger 35 adapted, when the operating member is in normal position, to engage behind the pin 27 which projects laterally from the pawl 25. A pin 36 which I have shown on the drawings in the form of a screw projects upwardly through a slot in the plate 16, the slot being shaped to permit a slight movement of the pin 36 in an outward direction sufficient to rock the pawl 25 on its pivot and withdraw the free end thereof out of engagement with the teeth on the number wheel. The pin 27 extends through the pawl 25 and projects at the opposite side thereof as shown in Fig. 5, and the free end of the pawl 28 is provided with a finger 37 which overlaps and rests against the pin 27. When the pawl 25 is withdrawn from engagement with the teeth on the number wheel as previously described, the pin 27 will move the free end of the pawl 28 sufficiently to disengage the shoulder or tooth 31 from the teeth 13 thereby permitting the number wheel to be rotated in a clockwise direction back to normal position. The return or resetting movement of the number wheel is accomplished by a coil spring 38 which has its inner end attached to the shaft 11 at 39 and its outer end secured at 40 to one end of the posts of the frame 41 in which the lower end of the shaft 11 is mounted. The shaft 11 is equipped at its upper end with a knurled button or head by means of which the number wheel may be manually returned to normal position if desired.

The machine is operated by means of a pencil or other similar instrument which may be engaged in the notch 18 corresponding to the number which it is desired to set up. The pencil is then moved, carrying with it the value member or operating member 17, until the pencil strikes against the adjacent radial edge of the cover plate 16. It will be evident that the distance that the pencil travels before striking the edge of the plate 16 will depend upon which of the notches 18 it is engaged with, the notch, of course, being determined by the number which it is desired to set up. The pawl 25, as has been previously described, is normally engaged with a tooth of the number wheel and operative movement of the value member will, through the instrumentality of this pawl, rotate or shift the number wheel a distance proportionate to the movement of the value member, thus upon successive movements of the value member, bringing the total of the numbers adjacent the notches, which have been engaged by the pencil during the operative movements, into view beneath the notch 15 in the plate 14. For instance, if an instrument is engaged in the notch adjacent the numeral 4 and the value member is depressed until the

instrument strikes the edge of the plate 16, the numeral 4 on the number wheel will be shifted to position beneath the notch 15. If upon the next actuation the instrument is 5 engaged with the notch adjacent the number 7 on the value member and the value member is depressed until the instrument engages the plate 16, the number wheel will be rotated or shifted seven numbers or sufficiently to bring the numeral 11 on the number wheel beneath the notch 15. It will be evident that long columns of single figures may thus be added and the total displayed to the operator. It will also be evident that 10 if it is desired to start out with a number consisting of two figures such as 22 for instance the pencil or instrument may be inserted in the space between the teeth 13 on the number wheel adjacent the number 22 15 and the wheel may be rotated in a counter-clockwise direction until the pencil engages the edge of the plate 14 adjacent the notch 15, thereby shifting the number wheel to bring the numeral 22 into view beneath the notch 15.

A hundred wheel 43 provided with spaced teeth 44 and having on its upper face numerals ranging from 1 to 9 inclusive, is rotatably mounted beneath the plate 16 so that 20 the numbers may be successively displayed through an opening 45 in the plate. Upon the shaft 11 adjacent the hundred wheel there is fixedly secured a disk 46 provided with a tooth 47 adapted to engage between 25 adjacent teeth 44 and impart a rotative movement to the hundred wheel. When, in the operation of the machine, the number wheel completes one revolution, the hundred wheel is moved one space to bring the 30 numeral 1 beneath the opening 45 by engagement of the tooth 47 with a pair of the teeth 44. Each revolution of the number wheel will impart a corresponding movement to the hundred wheel in the usual 35 manner. Upon rotation of the number wheel in a clockwise direction to normal position, the tooth 47 is brought into engagement with a blank 48 on the hundred wheel, as shown in Figs. 1 and 3, whereby said rotation of the number wheel beyond normal 40 position is prevented.

In order that upon actuation of the value or operating member the number wheel may not be carried by its inertia beyond its proportionate movement relative to the value member, I have provided a stop or overthrow mechanism which is thrown into operation to stop the movement of the number wheel when the value member reaches 45 the limit of its operative movement. The stop proper consists of a pin 49 projecting downwardly from a lever 50 fulcrumed at 51 and connected at 52 with a reciprocatory member 53. The pin 49, when the lever 50 55 is moved on its fulcrum to the position

shown in dotted lines in Fig. 6, engages between the adjacent teeth on the number wheel and prevents further rotative movement of the wheel. The reciprocatory member is provided with elongated longitudinally disposed slots 54 and 55 and a pair of pins 56 and 57 projecting downwardly from the cover plate 16 engage in the slots 54 and 55, respectively, and guide the reciprocatory member in its longitudinal movement. A 70 tension spring 58 secured at one end to a pin 59 on the elevated base of the machine and at its other end to the lever 50 retains the reciprocatory member and the stop lever normally in the positions shown in Figs. 1 75 and 3. In this position of the parts the elongated edge of the reciprocatory member adjacent the value member projects slightly beyond the radial edge of the cover plate 16, as shown in Fig. 1. When, during the actuation of the value member, the pencil or other instrument which is engaged in one of the notches 18 approaches the radial edge of the cover plate it strikes against the elongated edge of the reciprocatory member and 80 moves the same longitudinally thereby rocking the lever 50 upon its fulcrum and positioning the stop pin 49 between the number wheel teeth. This prevents overthrow of the number wheel beyond its required proportionate movement relative to the operating member and insures the stoppage of the number wheel with the proper numeral in position beneath the visual slot 15. When 85 the pencil or other instrument is removed 100 the stop mechanism is returned to normal position by the spring 58.

From the above description it will be evident that the value or operating member is moved a different distance before the operating implement engages the stationary cover plate 16, depending upon which of the notches 18 the implement is engaged with, and that the number wheel is moved a proportionate distance upon each actuation of 105 the value member by means of the pawl 25. It will also be evident that overthrow of the number wheel is prevented by engagement of the operating implement with the reciprocatory member 53 and that return movement of the number wheel with the value member is prevented by the latch 28. After 110 the column of figures has been added the number wheel may be restored to normal position by pressing laterally upon pin 36 to 115 withdraw pawls 25 and 28, as previously described.

While I have shown and described a preferred embodiment of my invention it will be obvious that various mechanical changes 120 in the details of construction and in the size and proportion of the various parts may be resorted to without departing from the spirit of the invention or sacrificing any of the material advantages thereof.

What I desire to claim is:

1. In an adding machine, the combination of a number wheel, an oscillatory value member adapted to be moved varying amounts proportionate to the number to be set up, said member being provided along one of its edges at varying distances from the center of oscillation of the said member with a plurality of serrations adapted to be engaged by the operator to move the said member, means limiting the movement of the said member in varying amounts corresponding to the serration engaged, and operative connections between the said member and the said wheel whereby the said wheel will be shifted an aggregated amount proportionate to the summation of the varied movements of the said member. 70
2. In an adding machine, the combination of a number wheel, an oscillatory value member adapted to be moved varying amounts proportionate to the number to be set up, said member being provided with an outwardly extending wing disposed along one side thereof and adjacent the outer end, said wing being provided along its outer edge at varying distances from its inner edge with a plurality of serrations adapted to be engaged by the operator to move the said member, means limiting the movement of the said member in varying amounts corresponding to the serration engaged, and operative connections between the said member and the said wheel whereby the said wheel will be shifted an aggregate amount proportionate to the movement of the said value member. 75
3. In an adding machine, the combination of a number wheel, an oscillatory value member adapted to be moved varying amounts proportionate to the number to be set up, said member being provided with an outwardly extending wing disposed along one side thereof and adjacent the outer end, said wing being provided along its outer edge at varying distances from its inner edge with a plurality of serrations adapted to be engaged by the operator to move the said member, means limiting the movement of the said member in varying amounts corresponding to the serrations engaged, and operative connections between the said member and the said wheel whereby the said wheel will be moved in a positive direction at each actuation of the value member a distance proportionate to the travel of the said member, means returning the said member to normal position after each actuation thereof, and means for locking the said wheel against return movement. 80
4. In an adding machine, the combination of a number wheel, an oscillatory value member adapted to be moved varying amounts proportionate to the number to be set up, said member being provided with an outwardly extending wing disposed along one side thereof and adjacent the outer end, said wing being provided along its outer edge at varying distances from its inner edge with a plurality of serrations adapted to be engaged by the operator to move the said member, means limiting the movement of the said member in varying amounts corresponding to the serrations engaged, and operative connections between the said member and the said wheel whereby the said wheel will be moved in a positive direction at each actuation of the value member a distance proportionate to the travel of the said member, means returning the said member to normal position after each actuation thereof, and means for locking the said wheel against return movement. 85
5. In an adding machine, the combination of a number wheel, an oscillatory value member adapted to be moved varying amounts proportionate to the number to be set up, said member being provided with an outwardly extending wing disposed along one side thereof and adjacent the outer end, said wing being provided along its outer edge at varying distances from the inner edge with a plurality of serrations adapted to be engaged by the operator to move the said member, means limiting the movement of the said member in varying amounts corresponding to the serrations engaged, and operative connections between the said member and the said wheel whereby the said wheel will be moved in a positive direction at each actuation of the value member a distance proportionate to the travel of the said member, means returning the said member to normal position after each actuation thereof, and means for locking the said wheel against return movement. 90
6. In an adding machine, the combination of a housing, a number wheel having a plurality of serrations disposed about its periphery, a value member adapted to be moved varying amounts proportionate to the number to be set up, operative connections between the said wheel and said member whereby the wheel will be moved in amount proportionate to the movement of the value member at each actuation thereof, means normally out of engagement with the said wheel adapted to be engaged therewith by movement of the said value member to prevent movement of the wheel in excess of the movement imparted thereto, said means comprising a member loosely mounted on the said housing, a pin adapted to engage one of the said serrations, means connecting the said pin to the said member, and yielding means holding the said pin normally out of engagement with the said wheel. 95
7. In an adding machine, the combination of a housing, a number wheel having a plurality of serrations disposed about its periphery, a value member adapted to be moved in varying amounts proportionate to the number to be set up, said member being provided with an

- the number to be set up, operative connections between the said member and the said wheel whereby the said wheel will be moved an amount proportionate to the movement 5 of the value member at each actuation thereof, and means normally out of engagement with the said wheel and adapted to be engaged therewith for preventing movement of the wheel in excess of the movement im- 10 parted thereto, said means comprising a lever having a pin at one end adapted to engage a serration on the periphery of the number wheel, a spring normally holding the said pin out of engagement with the 15 said wheel, and a member adapted to actuate the said lever against the force of the said spring, said member being connected to the said lever and loosely mounted within the housing and adapted to be actuated 20 by movement of the value member.
8. In an adding machine, the combination of a number wheel, an oscillatory member adapted to be moved varying amounts proportionate to the numbers to be set up, said 25 member being formed at varying distances
- from its center of oscillation to be engaged by the operator to move the said member, and an operative connection between the said member and wheel whereby the said wheel will be shifted an aggregate amount 30 proportionate to the summation of the varying movements of the oscillatory member.
9. In an adding machine, the combination of a number wheel, an oscillatory member adapted to be moved varying amounts proportionate to the numbers to be set up, said member being provided at one of its edges at 35 varying distances from its center of rotation with a plurality of serrations adapted to be engaged by the operator to move the 40 said member, and an operative connection between the said member and the said wheel whereby the said wheel will be shifted an aggregate amount proportionate to the summation of the varied movements of the said 45 member.
